CLAIM

The ornamental design for a ring, as shown and described.

DESCRIPTION

This design relates to a piece of jewelry, specifically a ring, incorporating two overlapping female-gender symbols and may be used as a civil-union ring, for example.

FIG. 1 is an offset frontal view of the invention;

FIG. 2 is a top view of the invention of FIG. 1;

FIG. 3 is a front view of the invention of FIG. 1; and,

FIG. 4 is a right side view of the invention of FIG. 1.
